UNITED STATES PATENT OFFICE.

GROSVENOR P. ROBINSON, OF SUMMIT, NEW JERSEY.

LIGHTING-FIXTURE.

1,363,919.

Specification of Letters Patent. Patented Dec. 28, 1920.

Application filed April 3, 1920. Serial No. 370,967.

To all whom it may concern:

Be it known that I, GROSVENOR P. ROBINSON, a citizen of the United States, residing at Summit, in the county of Union and State 5 of New Jersey, have invented an Improvement in Lighting-Fixtures, of which the following is a specification.

My invention relates to lighting fixtures of the semi-indirect character, particularly 10 ceiling fixtures.

In fixtures of this kind high efficiency incandescent lamps are employed, and in such fixtures generally in use the lamp is hung in a position above the translucent bowl and 15 surrounded by a reflector which directs the light upwardly upon the ceiling which again re-directs the light downwardly. Many ceilings are very poor reflectors. The object of my present invention is to provide a 20 lighting fixture of such construction that the relative positions of the lamp, bowl, and reflector or reflectors are such that the light from the lamp strikes both the inner and outer surfaces of the reflector or reflectors, 25 whereby the light is not only reflected upwardly against the ceiling, but is also reflected laterally, thereby greatly increasing its efficiency, while at the same time the filament is hid from direct view, and the light 30 blended in such manner that any unpleasant or injurious effect upon the eyes of the beholder is effectually prevented.

The details of the invention are herein-after particularly described.

35 In the accompanying drawings:—

Figure 1 is an elevation, partly in section, showing a lighting fixture embodying my invention.

Fig. 2 is a plan view of the same, partly 40 broken away.

Fig. 3 is an elevation, partly in section, showing the employment of a single reflector.

Fig. 4 is a plan view of the same, partly 45 broken away, and

Fig. 5 illustrates a modified form of support for the reflector.

Similar reference numerals indicate like parts in all the figures.

50 The lamp socket 10, is supported from the ceiling, or outlet box therein, in any desired manner.

11 indicates the socket cover, and 12, an incandescent lamp of high efficiency.

55 13, denotes a bowl, preferably of translucent material and thicker and somewhat

more shallow than the bowls usually employed in fixtures of this character.

This bowl may be hung by any suitable means, but I prefer to support it from the 60 socket cover by a common "harp" or frame comprising a plurality of spaced wire arms 14 (preferably three) the upper ends of which are secured to the socket cover by rivets 15, as shown, or in any other suitable 65 manner. These arms are bowed outwardly at their center to clear the lamp, and their lower ends are secured to a disk 16, provided with a centrally depending screw threaded lug 17, which extends through an opening 70 provided in the center of the bottom of the translucent bowl 13, for that purpose. 18 is a nut provided with a flange 19 which nut is screwed upon the end of the threaded lug 17, exterior of the bowl. If desired, a 75 washer 23, may be employed between the disk 16 and bowl 13.

22, indicates a reflector preferably of metal, open at the top and having a circular opening in its bottom of a size to surround the hanger arms 14, at their bowed centers. This reflector is substantially saucer-shaped and its upper part is of slightly larger diameter than the upper part of the bowl 13. In order to carry out my 80 invention it is important that this reflector be so positioned relatively to the lamp that its bottom cuts or divides the light emitted by the lamp in such manner that the light from the lamp strikes both the outer and 85 inner surface of the reflector, whereby the light will be reflected both laterally and upwardly.

20, denotes a ring L shaped in cross section which surrounds the wire arms 14, at their 90 bowed centers, said ring being secured to the respective arms in any suitable manner, preferably by rivets as shown.

It will be noticed that this ring 20, is positioned with respect to the bowl 13, so 100 that its flange 21, or horizontal portion is slightly below the top edge of the bowl and forms a seat for the reflector, bringing its bottom on a line with the center of the lamp filament.

105 In place of the ring 20, other equivalent means may be employed for holding the reflector in the required position, such as the angle-pieces 28, shown in Fig. 5, one of these being secured to each of the arms 14 by rivets 110 29, or other suitable means.

24, denotes another circular reflector,

preferably of metal, of appreciably larger dimensions than the reflector 22 and somewhat flared or spread at its upper part. This reflector 24, is open both at the bottom 5 and top; the bottom being of somewhat smaller circumference than the top of the reflector 22, and positioned level therewith. It is supported in such fixed relative position by a plurality of spaced links or connecting strips 25, (preferably three). These links are preferably metallic strips, one end being secured to the reflector 22, inside thereof, extending vertically above its top and then bent horizontally with the other 10 end secured to the reflector 24, on its inner surface. These links may be secured to the respective reflectors in any suitable manner, but I prefer to employ rivets 26 for that purpose, as shown. The links or connecting 15 members may also be of any other suitable shape or material.

Both the outer and inner surfaces of the reflectors are preferably painted or coated with white enamel.

25 In consequence of the relative positions of the reflectors, lamp and bowl, the light from the lamp strikes both sides of the reflectors whereby the light is not only reflected upwardly, but is also reflected laterally, the 30 filament being at the same time hid from direct view, and the light blended in such manner than any unpleasant or injurious effect upon the eyes of an occupant of the room in which the fixture is hung, is effectually prevented, while the full efficiency 35 of the lamp is utilized and the light augmented.

In some instances, it may be desired to make use of a single reflector as illustrated 40 in Figs. 3 and 4.

In such case it is preferable to make the reflector 27, of substantially the same shape and dimensions as the reflector 24, shown in Figs. 1 and 2, except that it is of somewhat

greater depth, the opening in its bottom being of a diameter to surround the bowed portions of the arms 14', and seat upon the flange 21, of the ring 20, (or upon the angle pieces 28, where such devices are employed,) whereby the bottom of such reflector will 50 cut or divide the light in the same manner as is done by the reflector 22, and with the same result.

By the employment of my invention, all the light emitted by the lamp is freely distributed without the lamp being visible, and there is no possibility of any unpleasant or injurious effect upon the eyes of a beholder.

I claim as my invention:—

1. In a lighting fixture, the combination 60 of a lamp and socket therefor, a socket cover, a bowl, arms secured at their upper ends directly to the socket cover and at their lower ends to the bowl within the same at its center for supporting said bowl, an upwardly flaring reflector provided with an opening in its bottom, and an angle-piece 65 secured to each of said arms for supporting the reflector with the edge of the opening in its bottom in a line through the center of the lamp filament whereby the light impinges upon both sides of the reflector.

2. In a lighting fixture, the combination 70 of a lamp and socket therefor, a socket cover, a bowl, arms secured at their upper ends directly to the socket cover and at their lower ends to the bowl within the same at its center for supporting said bowl, an upwardly flaring reflector provided with an opening in its bottom through which said 75 arms extend, and an angle-piece secured to each of said arms on a line through the center of the lamp filament and upon which the edge of the opening in the bottom of the reflector rests.

Signed by me this 31st day of March, 1920.

G. P. ROBINSON.
